F. D. SPEAR.
TRAFFIC SIGNAL.
APPLICATION FILED OCT. 6, 1916.

1,249,539.

Patented Dec. 11, 1917.

UNITED STATES PATENT OFFICE.

FURMAN D. SPEAR, OF NEW YORK, N. Y., ASSIGNOR TO ARMSPEAR MANUFACTURING COMPANY, OF NEW YORK, N. Y., A CORPORATION OF NEW YORK.

TRAFFIC-SIGNAL.

1,249,539.

Specification of Letters Patent. Patented Dec. 11, 1917.

Application filed October 6, 1916. Serial No. 124,156.

To all whom it may concern:

Be it known that I, FURMAN D. SPEAR, a citizen of the United States of America, residing at New York city, county and State 5 of New York, have invented a new and useful Traffic-Signal, of which the following is a specification.

My invention relates to a new and useful traffic signal, the object being to provide a 10 signal equally useful and available for day or night service and which in its preferred form by light, shape, color and word, gives the desired signal indication to "go" or "stop".

15 In the accompanying drawings:

Figure 1 is a side elevation of the complete device on a small scale and broken away at the center.

20 Fig. 2 is a similar view of the same parts in a different position.

Fig. 3 is a horizontal section on the line 3—3 of Fig. 1.

25 Fig. 4 is a sectional view of a lens detached.

1 represents the base of a suitable lantern having two sets of diametrically opposed red and green lens sectors. 2—2 represent the red sectors, while 3—3 represent the green sectors. These lens sectors are preferably of the spheroidal type designed to project an intense beam of substantial height, although it is not essential to the invention that any particular form of lens be employed. Bisection of the green lenses 3—3

35 are two semaphore plates or arms 4—4 carried by the lantern. Bisection of the red lenses 2—2 are two semaphore blades, plates or arms 5—5. Between the several lenses I

40 preferably locate guard plates 6—6. The semaphore arms are all radial to the vertical axis of the lantern. 7 is the head of the lantern. The lantern may be illuminated by an oil lamp or an electric lamp or any other illuminant, as desired. 8 is a pedestal which

45 supports the lantern and its associated parts. This pedestal 8 is rotatably mounted in a suitable base or standard 9. 10 is a handle on the pedestal 8 by which the lantern and its associated parts may be rotated at will. The

50 guard plates and semaphore arms are preferably braced by stiff horizontal rings 11—11. The semaphore arms 4 are of a different color, and preferably of a different shape and size, from the arms 5. The arms

55 4 should correspond in color to the lenses 2,

while the arms 5 should correspond in color to the lenses 3. If red is to designate the danger signal, the lenses 2 and the plates 4 should be colored red. If green is to designate the safety signal the lenses 3 and the 60 arms 5 should be colored green. The semaphore arms 4 may furthermore bear the words "Stop", while the semaphore arms 5 may bear the words "Go". By placing the lantern in substantially the same horizontal 65 plane with the semaphore arms 4 and 5 the light from the lantern illuminates the arms so that the words and shape may be observed, the color signal being furnished by the lens or glass. 70

By the use of this apparatus the officer in charge of traffic conditions at two cross roads may turn the signal so as to indicate with definiteness, either in the day time or in the night time, over which road vehicles shall 75 have the right of way.

The signal may be detachably connected to the top of the pedestal by any suitable clip devices such as conventionally illustrated at 12—12, or it may be made as a permanent fixture on the pedestal. 80

In operation, the semaphore arms 4—5, being made of relatively thin plate material and since they bisect radially the lenses adjacent to which they stand, they do not materially cut off or interfere with the light projected therefrom. The guard plates 6—6 are so arranged relatively to the lenses that when the signal is viewed as shown in Fig. 1, no part of the lenses 3—3 will be visible to 90 the one approaching. So also, when the signal is turned 90 degrees, or to the position shown in Fig. 2, the guard plates will hide the lenses 2—2 so that only the desired warning light will be exposed to the one approaching thereby avoiding all possibility of confusion. These guard plates are not essential to my invention in its broadest aspect. 95

It should be understood that I use the term "lens" in a broad enough sense to include any class, or the like. While I prefer to use what are now the conventional colors to denote danger and safety, namely, red and green, respectively, I do not intend to be limited thereto. 100

105 While my invention, as shown in the drawings, is of particular utility as employed for the purposes of traffic signaling at intersecting roads, its utility is not limited thereto and it may be employed in many 110

other connections for signaling purposes, traffic and otherwise, and the special method of mounting, supporting and operating the same may be modified at will.

5. What I claim is:

1. In a traffic signal of the character described, a lantern having two sets of lenses of different colors, one set being arranged in a plane at right angles to the other set, 30
10 one set of oppositely arranged semaphore arms carried by said lantern and bisecting the lenses of one set, and another set of differently shaped oppositely arranged semaphore arms bisecting the lenses of the other 35
15 set, and a rotatable support for said signal.
2. In a traffic signal of the character described, a lantern having two sets of lenses of different colors, one set being arranged in a plane at right angles to the other set, 40
20 two oppositely arranged semaphore arms carried by said lantern and bisecting the lenses of one set, and two other oppositely arranged semaphore arms bisecting the lenses of the other set, guard plates be- 45
25 tween said lenses extending outwardly from the lantern, and a rotatable support for said signal.
3. In a traffic signal of the character described, a lantern having two sets of lenses 50
55 of different colors, one set being arranged in a plane at right angles to the other set, two oppositely arranged semaphore arms carried by said lantern and bisecting the lenses of one set, and two other oppositely arranged semaphore arms bisecting the lenses of the other set, said lenses and arms being in substantially the same horizontal plane.

FURMAN D. SPEAR.
